US00D952099S

(12) **United States Design Patent** (10) **Patent No.:** **US D952,099 S**
Kim (45) **Date of Patent:** **** May 17, 2022**

(54) **SIDE SPRAYER**

(71) Applicant: **Spectrum Brands, Inc.**, Middleton, WI (US)

(72) Inventor: **Andy Kim**, Lake Forest, CA (US)

(73) Assignee: **Spectrum Brands, Inc.**, Middleton, WI (US)

(**) Term: **15 Years**

(21) Appl. No.: **29/735,706**

(22) Filed: **May 22, 2020**

(51) LOC (13) Cl. **23-01**

(52) U.S. Cl.

USPC **D23/226**

(58) **Field of Classification Search**

USPC ..... D23/213, 214, 223, 226, 228-230, D23/238-242, 249, 250, 255, 257 CPC B05B 1/16; B05B 1/1618; B05B 1/18; B05B 1/185; B05B 15/62; B05B 15/652; E03C 1/02; E03C 1/04; E03C 1/0405; E03C 1/0408; E03C 1/06; E03C 1/063; E03C 1/066; E03C 2001/0415

(57) **CLAIM**

The ornamental design for a side sprayer, as shown and described.

DESCRIPTION

FIG. 1 is a front perspective view of a side sprayer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area define the bounds of the claimed design and form no part thereof. The unshaded areas within the broken lines form no part of the claimed design.

1 Claim, 7 Drawing Sheets
